CARRIER PROJECTILE

Frank Larvick, Chicago Heights, Ill.

Application June 12, 1943, Serial No. 490,655

4 Claims. (Cl. 89—1)

My invention relates to the throwing of lines across bodies of water, to a ship in distress, and for other purposes, and has among its objects and advantages the provision of an improved line thrower.

In the accompanying drawings:

Figure 1 is a side view of a gun showing my invention applied thereto.

Figure 2 is a plan view of a gun barrel clamp.

Figure 3 is an end view of the clamp.

Figure 4 is an axial view of a line ring to be picked up by the projectile fired from the gun.

Figure 5 is an enlarged sectional view along the line 5—5 of Figure 2.

Figure 6 is a side and partial sectional view of a line carrying projectile and its shell.

Figure 7 is a partial sectional view of the projectile.

Figure 8 is a view illustrating the manner in which the line is picked up by the projectile, and

Figure 9 is a rear end view of the projectile.

In the embodiment of the invention selected for illustration, I make use of a clamp 10 comprising band sections 12 curved to fit on the muzzle end of the gun barrel 14. Each section has two flanges 16 through which bolts 18 are extended to frictionally secure the clamp to the barrel 14.

Arms 20 are respectively welded to the sections 10 and arranged longitudinally of the barrel 14, which arms are spaced apart some distance greater than the bore of the barrel 14. These arms extend beyond the muzzle end of the barrel 14 and constitute a mount for a carrier or ring 22 attached to a line 24 to be shot to a given location. This line is wound on a supply spool 26 in the usual manner.

Pins 28 are attached to the arms 20 to prevent the ring 22 from sliding back on the barrel 14, and the ring is prevented from dropping off the forward ends of the arms by springs 30 paralleling the respective arms. The rear ends of the springs lie in grooves 32 extending to the forward ends of the arms, and the springs are attached to the arms by screws 34. The springs yield and are pressed into the grooves 32 by the ring 22 when the latter is pulled off the arms.

In Figures 6, 7 and 8, two hooks 36 are pivotally connected with a pin 38 attached to a bracket 40 at the rear end of a projectile 42 of a shell 44. The bracket 40 is attached to a pin 44 secured to a bearing body 46 lying in a recess 48 in the projectile 42. This pin is coaxial with the projectile. Ball bearings 50 are confined between the body 46 and a second body 52 pressed into the recess 48. A retaining plate 54 is attached to the rear end face 56 of the projectile 42 by screws 58.

The hooks 36 lie in the explosive material 60

in the shell 44 and are biased apart by a coiled spring 62 mounted on the pin 38 and having ends 64 bent to engage over the hooks.

When the projectile 42 is fired from the barrel 14, the hooks 36 spread to connect with the ring 22 for carrying the line 24 to its destination. The bodies 46 and 52 and the bearings 50 constitute a thrust bearing, so that the hooks 36 are nonrotative notwithstanding rotation of the projectile 42 as it is fired from the barrel 14. Thus the hooks are prevented from rotating, which might cause damage to the arms 20.

No part of the line 24 lies inside the barrel 14, and the projectile is entirely independent of the line 24, or other device to be shot to a predetermined destination or target.

Without further elaboration, the foregoing will so fully explain my invention, that others may, by applying current knowledge, readily adapt the same for use under various conditions of service.

I claim:

1. The combination of a gun barrel, a projectile to be fired from the barrel, a carrier, spaced means having resilient devices at their free ends for releasably supporting the carrier at the muzzle end of the barrel, and hook means pivotally attached to the projectile, and means for spreading the hook means apart for connecting engagement with the carrier as the projectile is fired from the barrel.

2. The combination of a gun barrel, a projectile to be fired from the barrel, a carrier, arms extending forwardly from the gun barrel, spring means at the free ends of the arms for releasably supporting the carrier at the muzzle end of the barrel, hook means pivotally attached to the projectile, spring means for spreading the hook means apart angularly for connecting engagement with the carrier as the projectile is fired from the barrel, and a bearing interposed between the projectile and said hook means to render the hook means nonrotative with respect to the projectile.

3. The invention described in claim 1 wherein an explosive containing shell is provided, said projectile being attached to said shell, and said hook means lying in the explosive.

4. The invention described in claim 1 wherein said projectile has a recess in its rear end, a thrust bearing constrained in said recess, a bracket attached to one element of said thrust bearing, a pin attached to the bracket, said hook means comprising hooks pivotally mounted on said pin, and a spring mounted on said pin and engaging said hooks to pivot the latter to positions for engagement with said carrier.

FRANK LARVICK.
